J. A. B. SMITH

TYPEWRITING MACHINE

Filed Dec. 7, 1923

UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed December 7, 1923. Serial No. 679,069.

To all whom it may concern:

Be it known that I, JESSE A. B. SMITH, a citizen of the United States, residing in Stamford, in the county of Fairfield and 5 State of Connecticut, have invented certain new and useful Improvements in Typewriting Machines, of which the following is a specification.

The usual typewriter feed-roll release 10 mechanism comprises a key, usually near the end of the platen, which is effective to lock the feed-rolls in released position, for convenience in the removal and insertion of work-pieces in the machine. To obviate the 15 necessary movement of the operator's hand to the end of the carriage for releasing the feed-rolls from the platen, this invention provides for the same to be operated from any point along the front of the platen.

20 Such arrangement is especially valuable in typing on machines having long platen-carriages, as much time is lost in reaching for and finding the usual release-control lever or key when it is desired to withdraw 25 an individual sheet and insert another, since said key is at variable distances from the hand of the typist, according to the position of the carriage. It is also a valuable improvement in machines wherein the work- 30 sheets are inserted downwardly at the front of the platen, since the feed-rolls can be released during the sheet-inserting movement by the typist's finger or hand which is being used to insert the sheet.

35 Means are provided whereby the feed-rolls are only temporarily released and are automatically returned to the platen when the typist releases the device.

The invention comprises a bar extending 40 the full length of the platen, which supports an adjustable lever in such a manner that the feed-rolls are controlled from any position of the handle on said bar. The handle is also swingingly adjustable to be 45 conveniently operated either by the typist's finger or hand during the removing or inserting movement of the work-piece.

50 Another object of the invention is the provision of means whereby the release-control lever can be set at will, to be used for controlling the feed-rolls either to lock them in releasing position or to temporarily release same during the work-sheet-inserting movement. In this connection a feature of 55 the invention is the provision of means in

the form of a stop movable into or out of the path of the release-control means, thereby either limiting the same to temporarily release the feed-rolls or allowing the locking action of the feed-roll release to take place. 60

Other features and advantages will hereinafter appear.

In the accompanying drawings,

Figure 1 is a top plan view of the platen-carriage of an Underwood typewriting machine with the invention attached thereto. 65

Figure 2 is an end view, partly in section, of that shown in Figure 1, showing the feed-rolls in effective position, with the release-control lever set to be operated by the typist's finger, and the stop means positioned out of the path of the release-control means, to allow the locking action of the feed-roll release to take place upon operating said lever. 70

Figure 3 is a diagrammatic end view of the parts involving the invention shown in Figure 2, showing their position when the feed-rolls are locked in released position. 75

Figure 4 is a fragmentary end view of the platen-carriage and the release-control device attached thereto, partly in section, showing the release-control lever set to be operated by the typist's hand, and the stop means positioned in the path of the release-control means, to allow only temporary releasing of the feed-rolls to take place upon operating said lever. 80

Figure 5 is a diagrammatic end view of the parts involving the invention, showing the release-control lever and stop, as in Figure 4, and the feed-rolls in a temporarily released position corresponding thereto. 85

A platen 10, by means of an axle 11, is 90 journaled in the side pieces 12 of the platen-frame. This frame is shiftable up and down between case-positions by any suitable mechanism, not shown. For supporting the platen-frame and assisting in the case-shift 95 of the latter, pins 13 on the side plates of the platen-frame are set upon arms 14 fast to a rock-shaft 15, upon which shaft is a spring, not shown, tending to lift the platen-frame. The case-shifting mechanism may be 100 that shown in the standard Underwood typewriting machine. 105

The platen-frame is also provided with a paper-shelf 16, which forms an extension of the usual rear paper-table 17 and apron-extension 18, for guiding work-pieces down be- 110

hind the platen and around under the same to the printing line at the front thereof. The usual front and rear feed-rollers 19 and 20, respectively, are also provided. The 5 front rolls 19 are on a shaft 21, seated on the arms 22 of bell-crank levers pivotally mounted on a shaft 23, supported on the end plates 12 of the platen-frame. The rear feed-rolls 20 are on a shaft 24, seated on the arms 25 10 of the bell-crank levers also pivotally mounted on the shaft 23. The bell-crank levers, which comprise the arms 22 have other arms 26 which depend to the rear of a shaft 27; and the bell-crank levers which comprise the 15 arms 25 have other arms 28 which depend to the front of the shaft 27. Leaf-springs 29, bearing upon the arms 22 and 25, tend to rock the arms upward to throw the feed-rolls against the platen, and therefore tend 20 to press the arms 26 and 28 against the shaft 27. The shaft 27 has flats 30 cut therein where the arms 26 and 28 engage the same. When the feed-rolls are in effective position, the arms 26 and 28 bear against the flats 30, 25 as shown in Figure 2. When, however, the shaft 27 is rotated, the arms 26 and 28 are forced apart to draw down the feed-rolls 19 and 20, as shown in Figure 3. The shaft 27 is journaled in the side plates 12 of the 30 platen-frame (not shown). The feed-roll mechanism, just described, is that found in the standard Underwood typewriting machine.

The feed-rolls 19 and 20 may be thrown off the platen 10 by means of a release-control lever 43 of a control-device 42 through the following interconnecting parts. Fast to the shaft 27 is an arm 31, which is connected at one end to a link 32; the other end of the 35 link 32 being connected to a bell-crank lever 33 on a stub-shaft 34, mounted in the right-hand side plate of the platen-frame. One arm 35 of the bell-crank lever 33 connects with the control-device 42 by a forwardly-extending link 36. The release-control device 42 in addition to lever 43 may comprise a bar or rock-shaft 39 on which lever 43 is 40 slidably mounted and has securely fastened on the right-hand end thereof an arm 38, to which the forward end of link 36 is 45 connected. The rock-shaft 39 extends the entire length of the platen 10, and, at its ends, has bearings in a bracket 40 suitably secured along the side pieces 41 of the platen-carriage. Pressure on the lever 43 of the 50 control means 42, as by the finger of the typist when in the position shown in Figure 2, or by the palm of the hand when in the position shown in Figure 4, results in the movement of the same to cause the link 36 to be 55 drawn forward, bell-crank arm 35 to be rocked counterclockwise, and the link 32 to be drawn to release the feed-rolls.

It will be noted that the link 36, which 60 connects that part of the feed-roll-releasing

mechanism which is on the shiftable platen-frame to that part of the feed-roll-releasing mechanism which is on the carriage, is slightly inclined downward and rearward when the shift-frame is in lower-case position. 65 When the shift-frame is in upper-case position, this link 36 is inclined slightly upward and rearward; the true medial position of the link 36 being a horizontal position half-way between its case-positions. By this 70 means, provision is made for the same roll-releasing action of the parts whatever the case-position of the shift-frame. It will be understood that the carriage has movement, in the usual manner, in letter-feed and return directions, on the main frame 48 of the machine. At its rear, the carriage rides upon a rail 49 on the main frame, and, at its front, the carriage is provided with a roll 50, which travels on a runway 51 on the 75 main frame 48.

The control-lever 43 may comprise a collar-portion 44, at the lower end thereof, embracing rock-shaft 39, and a thumbscrew 45 threaded into the upper side of the collar 44. 80 The leading end of screw 45 is conical in shape and is arranged to fit into either of two spaced V grooves 46^a or 46^b extending longitudinally of rock-shaft 39. When the screw 45 is set to be guided in groove 46^a, the lever 43 is held in upstanding position (see Figures 1 and 2), and it may be operated conveniently by the finger of the typist during the sheet-inserting movement, and when fitted into groove 46^b, if properly positioned said lever 43 to be operated by the palm of the typist's hand. 85

The control-release means comprising device 42 may also include a pivoted stop 65, suitably mounted from the side pieces 41 of the platen-frame, as on a downwardly and forwardly extending plate-portion 66 of bracket 40. Stop 65 may be set at will in the path to intercept a lug 67 fastened to rotate with the rock-shaft 39. When the stop 65 is positioned in the path of lug 67, as shown in Figure 4, pressure on lever 43 will cause shaft 39 to be rotated only enough to temporarily displace the feed-rolls 19 and 20 from the platen 10, as shown in Figure 5. On removal of the pressure on lever 43, the feed-rolls 19 and 20 will automatically be returned to their normal effective position by reason of the rotative effect due to the pressure of the springs 29, exerted through arms 26 and 28, upon the diagonally opposite edges of the flattened portions 30 of shaft 27. When the stop 65 is positioned out of the path of lug 67, as shown in Figure 2, pressure on lever 43 will allow the unrestricted movement for displacing the feed-rolls 19 and 20 to take place, as shown in Figure 3. In this case, the pressure of the arms 26 and 28 will be exerted parallel to the flattened portions 30, that is, against the narrow edges 100

thereof, and will therefore cease to have any rotative tendency on shaft 27, and the parts will remain in such locked position with the feed-rolls 19 and 20 thrown off platen 10.

5 Suitable detent means, such as detent-holes 63, may be provided on the plate-portion 66 to engage a projecting point 62 on stop 65 for holding the stop 65 in or out of effective position.

10 In the drawings, a record-sheet 52, faced by a carbon-sheet 53, is shown as having been fed down the table 16 and around the platen 10, and as having the typed portion thereof extending rearward over the top of the platen 10. The record-sheet 52 receives the entries made successively upon a series of individual cards, bill or statement sheets 71; and, in order that the record-sheet 52 may be held in place upon platen 10 while the feed-rolls are released for the insertion or removal of a statement-sheet 71, a pair of clips are provided. These clips are shown as consisting of spring-fingers 55 having a roller 56 on each, which are adapted to bear upon the record-sheet 52 on platen 10. The spring-fingers 55 are suitably supported on a shaft 58, as by screws 57. The shaft 58, in turn, is supported by U-shaped brackets 59, secured to blocks 60 on the side plates 61 of a frame which is set upon and detachably secured to the top sides of the side pieces 12 of the platen-frame.

15 The shaft 58 also serves as a support for a front paper-table 70, which acts as a guide and gage for the statement-sheets 71. For supporting the table 70 on the shaft 58, there is riveted to the rear wall of the table a bar 75. This bar, beyond the sides of the table 70, has its ends offset downward at 76, and rearward at 77, for attachment to U-shaped brackets 78, similar to the brackets 59. These brackets 78 are connected to the shaft 58 by rollers 79, set in the slot 64 in the shaft 58, and held therein by springs 80. Although, if desired, this form of attachment of the table 70 to the shaft 58 permits angular movement of the table 70, the prime purpose of such attachment is to permit the table 70 to be slid rightward or leftward along the shaft 58 to any desired position on the carriage. The rollers 79 and slot 64 obviously make a spline connection of the table 70 to the shaft 58; and the pressure of the springs 80 is sufficient to hold the table against accidental rightward or leftward displacement. It follows, therefore, that the table 70 is placeable and detachable as a unit with the frame which carries the shaft 58 and paper-clips 55; so that, when this detachable frame is not present on the machine, the machine may be used in the ordinary way without unnecessary incumbrances.

20 The shaft 58 is revolute in the brackets 59, which are similar in construction to the

brackets 78, so that the spring-fingers 55 and the front paper-table 70 may be rotated with the shaft 58 as a unit on the brackets 59 for temporarily displacing the same away from the platen 10.

25 In typing on well-known work-piece forms comprising the card, statement or bill sheet 71 which is to be inserted from the front of the machine against a record-sheet 52 on platen 10, the record-sheet 52 and the carbon 53 are first fed around the platen to typing position, while the feed-rolls 19 and 20 are in effective position, by means of the usual hand-wheels 81 on the platen-axle 11, or by means of the usual line-space mechanism (not shown). The spring-fingers 55, if not previously applied, are then applied to the record-sheet 52 and carbon 53, and the stop 65 is set to intercept lug 67, as shown in Figure 4. The lever 43 is slidingly adjusted on the rock-shaft 39 to a convenient operating position adjacent the record-sheet 52 (see Figure 1), and is set either to be operated by the typist's finger, with the screw 45 fitted in groove 46, as shown in Figure 2, or by the typist's palm, with the screw 45 in groove 46^a, as shown in Figure 4. If it is assumed that the lever 43 is arranged in position for operation by the typist's palm, as shown in Figure 4, the typist then passes a statement-sheet or card 71 in front of the carbon-sheet 53 on platen 10. As the typist's hand moves downward, his palm strikes the lever 43 and throws off the feed-rolls 19 and 20, permitting the lower edge of the statement-sheet 71 to pass around the platen 10 between the latter and the apron 18. When the statement-sheet 71 is in printing position on the platen 10, the typist's hand is lifted to release the lever 43 and to permit the springs 29 to throw the feed-rolls 19 and 20 to position for holding the statement-sheet 71.

30 After typing on a statement-sheet 71 is completed, the carriage is thrown rightward for commencement of writing on another statement-sheet. The lever (not shown), by which the carriage is thus returned, ordinarily effects a single line-space movement of the platen 10 by mechanism not here shown. This results in a line-space movement of the record-sheet 52 and carbon 53 so as to prepare the same for receiving the entries to be made upon the next succeeding statement-sheet.

35 In the above-described operation, the control-lever 43 may be fitted in groove 46^a instead of 46, as shown in Figures 2 and 3, in which case, the typist's hand, as it moves downward during the inserting movement of the statement-sheet 71, will have its little finger conveniently positioned for pressing lever 43 forwardly to throw off the feed-rolls 19 and 20. When the statement-sheet 71 is 40 in printing position on the platen 10, the

4 typist lifts his hand and releases the pressure on lever 43 to permit the feed-rolls 19 and 20 to automatically return to their effective position.

- 5 The above description explains the operation of a type-writing machine embodying the invention for typing a relatively complex work-piece. It is obvious that simpler and ordinary forms may be typed with equal 10 advantage on the arrangement shown, and, if necessary, the front paper-table 70 and its supporting framework may be removed, thus leaving a standard typewriting machine. In typing any forms, if desired, the stop 65 15 may be moved out from the path of the lug 67, as shown in Figure 2, to allow the locking of the feed-roll-release to take place, as shown in Figure 3, when the control-lever 43 is operated.
- 20 The invention as shown is readily attached to the feed-roll-release control mechanism of any standard machine, and its adjustability facilitates the typing operation by providing a control means that is more conveniently arranged than any heretofore.

Variations may be resorted to within the scope of the invention, and portions of the improvements may be used without others.

Having thus described my invention, I 30 claim:

1. In a typewriting machine, a platen, a platen-carriage, a releasable work-piece-feeding mechanism co-operating with the platen, and control means for releasing said mechanism, comprising a bar mounted on 35 the carriage extending lengthwise of the platen, and a lever slidably mounted on the bar for controlling the releasing of said mechanism from positions in front of the 40 platen.

2. In a typewriting machine, a platen, a platen-carriage, a releasable work-piece-feeding mechanism co-operating with the platen, and control means for releasing said mechanism, including a bar mounted on the 45 carriage extending lengthwise of the platen, a lever mounted on the bar for controlling the releasing of said mechanism from different positions in front of the platen, and 50 means for securing said lever in a plurality of angular positions transversely of the bar.

3. In a typewriting machine, a platen, a platen-carriage, a releasable work-piece-feeding mechanism co-operating with the platen, a control device for releasing said mechanism, including a bar extending 55 lengthwise of the platen, and a lever mounted in a slidable relation to the bar for controlling the releasing of said mechanism, 60 said lever including means for securing it in a plurality of angular positions transversely of the bar, and means settable to limit the movement of the control device to produce a temporary release of said mechanism during 65 the operation of said device, and automatic

return to its operating position, said control device normally movable to an extreme position in which said mechanism is locked in released position.

4. In a typewriting machine, a platen, a platen-carriage, a releasable work-piece-feeding mechanism co-operating with the platen, and control means for releasing said mechanism, said control means having a 70 mounting on the carriage and movable to 75 different adjusted positions longitudinally thereof.

5. In a typewriting machine, a platen, a platen-carriage, a work-piece-feeding mechanism co-operating with the platen, and control means for releasing said mechanism, including a bar extending lengthwise of the 80 platen, and a lever mounted to operate the bar at different points along the bar.

6. A revoluble-platen typewriting machine having a releasable work-piece-feeding mechanism in co-operation with the platen, in combination with a control means comprising a rock-shaft extending lengthwise of the platen connected to move said mechanism for controlling the release thereof, a lever slidably mounted on the rock-shaft for operating the same from any position therealong, a projecting lug rigidly fastened to move with the rock-shaft, and a stop settable into and out of the path of the lug, said stop, when in the path of the lug, limiting the movement thereof to cause only temporary release of said mechanism on 95 operation of the lever, and thereafter permitting said mechanism to return to its effective position, and when out of the path of the lug allowing said mechanism to be locked in released position on operation of 100 said lever.

7. A revoluble-platen typewriting machine having a releasable work-piece-feeding mechanism co-operating with the platen, in combination with a control device comprising a rock-shaft extending lengthwise of 110 the platen connected to move said mechanism for controlling the release thereof, a lever slidably mounted on the rock-shaft, and a plurality of spaced grooves extending lengthwise of the rock-shaft, means on said 115 lever for engaging said grooves for operating the rock-shaft, said lever being angularly adjustable on said rock-shaft to correspond with any one of said grooves to enable operation of the lever by various parts 120 of the typist's hand during the removing or inserting movement of a work-piece in the machine.

8. A revoluble-platen typewriting machine having a releasable work-piece-feeding mechanism co-operating with the platen, in combination with a control means comprising a rock-shaft extending lengthwise of the platen connected to move said mechanism 125 for controlling the release thereof, a lever 130

slidably mounted on the rock-shaft, a plurality of spaced grooves extending lengthwise of the rock-shaft, means on said lever for engaging said grooves for operating the 5 rock-shaft, said lever being angularly adjustable in said rock-shaft to correspond with any one of said grooves to enable operation of the lever by various parts of the typist's hand during the removing or inserting 10 movement of a work-piece in the machine, a lug rigidly fastened to move with said rock-shaft, and a stop settable into and out of the path of the lug, said stop when in the path of the lug limiting the movement 15 thereof to cause only temporary release of said mechanism on operation of the lever, and thereafter permitting said mechanism to return to its effective position, and when out of the path of the lug allowing said mechanism 20 to be locked in released position on operation of said lever.

9. In a typewriting machine, a platen, feed-roll mechanism co-operative with the platen, a releasing bar operatively connected 25 to said feed-roll mechanism, said releasing bar extending longitudinally of the platen, and a member for operating said releasing bar, said member and said releasing bar having 30 slidable relation to each other so that said feed-roll mechanism is operable in different relative positions of said releasing bar and member.

10. In a typewriting machine, a platen, feed-roll mechanism co-operative with the platen, a releasing bar operatively connected 35 to said feed-roll mechanism, said releasing bar extending longitudinally of the platen, a member for operating said releasing bar, said member and said releasing bar having 40 slidable relation to each other so that said feed-roll mechanism is operable in different relative positions of said releasing bar and member, said feed-roll mechanism including locking means, and said releasing bar normally 45 movable to an extreme position to

operate said locking means, and a stop settable to operatively engage said releasing bar to prevent operation of said locking means and produce temporary release and automatic return of said releasing bar. 50

11. In a typewriting machine, a platen, a releasable work-piece-feeding mechanism co-operating with the platen, said mechanism including a locking device, a control device to release said mechanism, and means settable to limit the movement of said control device to cause temporary release and automatic return of said mechanism. 55

12. In a typewriting machine, a platen, work-piece-feeding mechanism co-operating 60 with the platen, releasing means for said mechanism, and means settable to limit the movement of the releasing means for automatic return of said mechanism, said releasing means normally movable to an extreme 65 position for locking said mechanism in released position.

13. In a typewriting machine, a platen, a platen-carriage, feed-rolls for co-operating 70 with the platen, means for releasing the feed-rolls including a control lever, a mounting on the carriage for said control lever, said control lever adjustable to different positions lengthwise of the platen, means for adjusting the control lever to different positions transversely of said mounting, and means settable to limit the releasing movement of said control lever. 75

14. In a typewriting machine, a platen, a platen-carriage, a frame for the platen 80 mounted on the carriage, means for shifting the platen-frame between case-positions on the carriage, feed-rolls, carried by said shiftable platen-frame, to co-operate with the platen, and control means mounted on the 85 carriage for releasing the feed-rolls, said control means movable to different actuating positions.

JESSE A. B. SMITH.
